United States Patent Office.

IRVINE CARMAN, OF SANDWICH, ILLINOIS.

Letters Patent No. 89,972, dated May 11, 1869.

IMPROVEMENT IN HORSE-RAKES.

The Schedule, referred to in these Letters Patent and making part of the same.

To all whom it may concern:

Be it known that I, IRVINE CARMAN, of Sandwich, in the county of De Kalb, and in the State of Illinois, have invented a certain new and useful Improvement in Horse Hay-Rake; and do hereby declare that the following is a full, clear, and exact description thereof, reference being had to the accompanying drawings, and to the letters of reference marked thereon.

The nature of my invention consists in the construction and general arrangement of a "horse hay-rake," which will be hereinafter fully set forth.

In order to enable others skilled in the art to which my invention appertains, to make and use the same, I will now proceed to describe its construction and operation, referring to the annexed drawings, which form a part of this specification, and in which—

Figure 1 is a side view in section, and

Figure 2, a plan view.

Figure 3 is a rear elevation of the driver's seat.

A represents the axle, to the ends of which the wheels B B are attached.

From about the centre of the axle A two bars, C C, extend upward, on the top of which bars a small platform, D, is secured, said platform being further braced by two braces, E E, the lower ends of which are secured to the foot-board F, laid across the shafts G G.

To the front edge of the platform D the seat H is hinged, the rear edge of said seat resting on two bars, a a, pivoted to it.

The bars a a extend downward, and are, at their lower ends, pivoted to small bars b b, projecting from the rake-roller I, which runs parallel with, and a suitable distance above the axle A.

The rake-roller I has its bearings in suitable journal-boxes, secured near each end of the axle A.

Near the small bars b b, on the rake-roller I, are two other bars c c, to the upper ends of which, other bars, d d, are pivoted.

These latter bars, d d, are at their upper ends connected by a cross-piece, J, forming the back for the driver when seated on his seat H.

The bars d d are notched on the rear side, and pass through loops x x, on the rear side of the platform D, so that the said bars may move freely up and down, but at the same time preventing the back J from giving away when the driver leans against the same.

The notches in the bars d d, catching in the loops x x, allow the back J to be regulated or placed in any position desired.

The teeth e e, forming the rake, are secured to the rake-roller I in any desired manner, and are supported by springs f f.

The teeth e e are formed of substantial spring wire, and the supporting-springs are made of the same material.

The springs f f are placed around the teeth e e where they enter the roller I, and bent over toward the seat, then underneath, around the roller, back to the teeth, one end being attached above the other, thus rendering two distinct supports.

It will be seen that when the driver is seated on the seat H, and his back leaning against the rest J, the weight on the bars a b and c d presses the teeth of the rake down, and holds them to their work.

For the purpose of raising the teeth up from the ground, the roller I is provided with a bar, g, which, by means of a rod, h, is connected with a lever, i, said lever being pivoted to a standard on the foot-rest F.

By moving the lever i toward the seat, the roller I turns in its bearings, so that, when the driver sits down on the seat, the weight operates on the front side of the roller instead of on the rear, as before, thus enabling him to keep the rake-teeth up from the ground whenever desired.

Having thus fully described my invention, What I claim as new, and desire to secure by Letters Patent, is—

1. The hinged seat H, with supporting-bars a a, connecting-bars b b, and the rake-roller I, all substantially as and for the purposes herein set forth.

2. The rest J, supporting-bars d d, connecting-bars c c, and the rake-roller I, with teeth e e and springs f f, all arranged and operating substantially as and for the purposes herein set forth.

In testimony that I claim the foregoing, I have hereunto set my hand, this 29th day of January, 1869.

IRVINE CARMAN.
